William P. Sampson

UNITED STATES PATENT OFFICE.

WILLIAM P. SAMPSON, OF KANSAS CITY, MISSOURI, ASSIGNOR OF ONE-HALF
TO PIERRE S. BROWN, OF KANSAS CITY, MISSOURI.

REIN-HOLDER.

SPECIFICATION forming part of Letters Patent No. 709,855, dated September 23, 1902.

Application filed May 22, 1902. Serial No. 108,568. (No model.)

To all whom it may concern:

Be it known that I, WILLIAM P. SAMPSON, a citizen of the United States, residing at Kansas City, in the county of Jackson and State 5 of Missouri, have invented certain new and useful Improvements in Rein-Holders and Clamp-Holders; and I do hereby declare that the following is a full, clear, and exact description of the invention, such as will enable 10 others to make and use the same, reference being had to the accompanying drawings, forming a part of this specification.

The object of my invention is to provide a spring clamp or holder for the purpose of 15 securing or holding the reins or "lines" of a harness (when attached to a vehicle and when not in use) and to provide a graduated or limited clamp or holder which will firmly hold up to a certain pressure of resistance 20 all substances placed between its arms by means of a new and novel construction and combination of two metal arms branching from a common base, so shaped and placed opposite each other and so constructed all 25 from a single piece of metal as to obtain equalizing and opposing pressure, securing in the action of the two arms the combined qualities both of a spring and a clamp; and it consists of the new and novel construction 30 of parts, such as will be more fully described and specifically pointed out in the claims. I attain these objects by the mechanism illustrated in the accompanying drawings.

In the drawings, Figure 1 is a view in perspective of my improvement in rein-holders and clamp-holders. Fig. 2 is an end view showing one of the bolts which secures the device to the dashboard or other portion of a vehicle or other object, as may be desired. 40 Fig. 3 is a detail view in perspective when in operation, showing the upper or outer spring-arm overlapping the lower or inner spring-arm and the upper or outer spring-arm being secured to the body of the device by a stay-bolt or pin, which also prevents the reins or lines or other substance from passing beyond it. Fig. 3 also shows the four arms equidistant from each other and bent in a U-shaped form for the purpose of clamping to a dashboard or other portion of a vehicle or other object.

Referring to the drawings, the letters A' and A², respectively, represent the upper (or outer) and the lower (or inner) spring-arms, between which the reins (or other object) C are to be secured. These spring-arms consist of either flat or half-oval narrow plates of suitable length and thickness extending from the base of the holder at either end and curved outwardly and inwardly until one 55 overlaps the other about two-thirds their length, the upper or outer end being slightly curved upward or outward for convenience or ready adjustment in placing the reins or other object C between the arms. The inner 60 or contact surfaces D of these spring-arms may be milled or corrugated for the purpose of greater security in preventing the reins C from slipping when placed therein.

In Fig. 3, E represents the four U-shaped 70 arms with holes F near their outer ends for the reception of bolts for the purpose of clamping to dashboard or other portion of a vehicle or other object. The upper or outer spring-arm A' is provided with a hole (not 75 shown) D about two-thirds its length distant from the end, through which a headed bolt or pin B passes, the lower (or inner) spring-arm A² having a slotted or oblong hole (not shown) near its outer end and directly beneath the hole in the upper or outer spring-arm, 80 which also receives said bolt B. Bolt B then passes into and through the base of the holder B² and is riveted or otherwise securely fastened.

Having fully described my invention, what I now claim as new, and desire to secure by Letters Patent, is—

1. In a rein or "line," holder, the combination of a base-plate with four U-shaped arms 90 curved in U form equidistant from each other with holes near their outer ends in combination with two narrow spring-arms formed from a portion of the base-plate and extending from the ends of said base-plate and 95 curved outwardly and back until one overlaps the other, the end of the outer lapped spring-arm being curved slightly upward or outward, a hole through both of said spring-arms and a bolt or pin passing through both, 100 the hole in the lower or inner spring-arm being slotted or made oblong for free movement

of said arm on the bolt or pin which passes through it, all substantially as set forth.

2. In a rein-holder the combination of two spring - arms formed from a portion of the base-plate and curved oppositely from the four **U**-shaped arms, returning until one overlaps the other and when held by a securing-pin causing a strong spring-pressure between the two surfaces in contact.
3. In a rein-holder the combination of a base-plate with four **U**-shaped arms curved in **U** form equidistant from each other with holes near their outer ends in combination

with two spring-arms having corrugated or milled faces on their contact-surfaces, they being held firmly together by a pin or bolt, said bolt also preventing the reins from passing over and beyond the spring-surfaces.

In testimony whereof I have signed my name to this specification in the presence of two subscribing witnesses.

WILLIAM P. SAMPSON.
